UNITED STATES PATENT OFFICE.

HAMITAGE L. RICHARDSON, OF SEBRINGVILLE, ONTARIO, CANADA.

TATTING SHUTTLE.

Application filed May 16, 1922. Serial No. 561,498.

To all whom it may concern:

Be it known that I, HAMITAGE L. RICHARDSON, a citizen of the Dominion of Canada, and resident of Sebringville, in the county 5 of Perth and Province of Ontario, Dominion of Canada, have invented certain new and useful Improvements in Tatting Shuttles, of which the following is a specification.

The invention has relation to certain new 10 and useful improvements in a tatting shuttle and has for its primary object the provision of a shuttle of this character which will be of improved and simplified construction and will also permit of a full winding of the 15 shuttle bobbin without danger of the thread catching within the shuttle during use of the same.

The invention has for another object the provision of a tatting shuttle of the character 20 stated, in which the bobbin will be provided on its outer end with a protecting flange of sufficient diameter to prevent thread on the bobbin from passing over the protecting flange and becoming caught on 25 the locking flanges carried at the end of the bobbin to receive the removable side of the shuttle.

A further object of the invention resides in the provision of a tatting shuttle of the 30 character set forth in which the protecting flange will be arranged so as not to interfere with attachment or removal of the removable side of the bobbin.

The invention has for a still further object 35 the provision of a tatting shuttle which will be of extremely inexpensive construction, as well as highly efficient in use and which may be employed in the same manner as the shuttles now in use.

With the foregoing and other objects in 40 view, as will appear as the description proceeds, the invention consists in the novel construction, combination and arrangement of cooperating elements as hereinafter more specifically set forth, claimed and shown in 45 the accompanying drawings forming a part of the present application and in which:

Figure 1 is a plan view of the removable side of the shuttle, looking at the inner face 50 thereof.

Figure 2 is a perspective view of the shuttle with the removable side taken off.

Figure 3 is a longitudinal section through 55 the shuttle with the parts thereof assembled.

Referring more in detail to the drawings, in which similar reference characters design-

uate corresponding parts throughout the several views, 4 indicates the bobbin carrying side of the shuttle and on which is mounted centrally the tube 5. The removable side 6 of the shuttle is adapted to be locked upon the free end of the tube 5, as will be apparent by referring to the drawings. It will also be understood that the shuttle side 4 carries at its pointed end the 60 usual shuttle pin 7. It will also be seen by referring to Figure 3 that the tube 5 has a transverse passage 8 through which the end of the thread may be extended for the purpose of securing the thread on the shuttle 65 tube 5.

In order to secure the side 6 of the shuttle to the tube 5, this shuttle side 6 has a pair of securing lugs 9 struck out therefrom on opposite sides of the perforated centre 10 of the side 6. The lugs 9 are adapted to be engaged between the ends of the opposite arcuate flanges 11 carried by the outer bobbin head 12. The side 6 must be placed across the outer end of the tube 5 at right 70 angles to the bobbin side 4 to bring the lugs 9 between the ends of the flanges 11. These flanges 11 are offset slightly from the bobbin head 12, as shown in Figure 3. The flanges 11 have outwardly offset locking portions 13 75 into which the locking lugs 9 are seated when the shuttle side 6 is given a quarter turn to bring the same parallel with the bobbin side 4 after positioning the locking lugs 9 between the ends of the locking flanges 11. 80

In order to protect the thread on the bobbin 8 and prevent the thread from becoming caught on the locking flanges 11 and locking lugs 9, a protecting flange 14 is carried on the outer end portion of the tube 5 85 inwardly of the bobbin head 12. The diameter of the protecting flange 14 should be at least equal to the diameter of the head 12, including the flanges 11 thereof. It is to be understood that the shuttle is of the usual configuration and may be employed in the same manner as the shuttle now in general use for this purpose. By removing the shuttle side 6, the bobbin 5 may be filled 90 with the desired thread, to the level of the bobbin flange 14 and the shuttle then employed without danger of the thread becoming caught on the locking flanges 11 and locking lugs 9. 95

In this improved form of tatting shuttle, it is not necessary to remove 100 and replace the bobbin.

It is believed the complete construction

and operation of the present invention may be clearly understood from the foregoing paragraphs without further description. It is to be understood that while the preferred embodiment of the invention has been shown and described, minor changes in the details of construction and arrangement of parts may be resorted to within the scope of what is claimed without departing from the spirit of the invention.

What I claim as new is:

1. A tatting shuttle comprising a shuttle side member, a bobbin carried by said shuttle side member, a removable side member, attaching means for said removable side member and a thread protecting flange carried by said bobbin adjacent the shuttle side.
- 15 2. A tatting shuttle comprising a body

member, a bobbin mounted on one face of said body member, a second body member, 20 said bobbin including an outer head with arcuate flanges extended therefrom and slightly offset from the head, said flanges having outwardly offset central locking portions, said second shuttle body member having locking lugs adapted to ride over said flanges and seat in the outwardly offset central locking portions thereof, and a thread protecting flange carried by said bobbin adjacent said outer head of the bobbin to prevent thread carried on the bobbin from catching on said flanges of the bobbin head and said locking lugs of the second mentioned shuttle body member.

In testimony whereof, I affix my signature.

HAMITAGE L. RICHARDSON.
